UNITED STATES PATENT OFFICE.

CHARLES OSBORNE ELLIS AND EDWARD WILLIAM WILKINSON, OF BIRMINGHAM, ENGLAND.

EJECTOR MECHANISM FOR BREECH-LOADING FIRE-ARMS.

SPECIFICATION forming part of Letters Patent No. 394,844, dated December 18, 1888.

Application filed January 27, 1888. Serial No. 262,174. (No model.) Patented in England May 18, 1887, No. 7,222.

To all whom it may concern:

Be it known that we, CHARLES OSBORNE ELLIS and EDWARD WILLIAM WILKINSON, gun-manufacturers, subjects of the Queen of Great Britain, residing at Birmingham, England, have invented certain new and useful Improvements in Ejector Mechanism for Breech-Loading Small-Arms, (for which we have applied for Letters Patent in Great Britain, numbered 7,222, dated May 18, 1887;) and we do hereby declare the following to be a full, clear, and exact description of the invention, reference being had to the accompanying drawings, which form part of this specification.

This invention relates to improvements in ejector mechanism of breech-loading small-arms of the kind commonly called "drop-down" guns.

Figure 1 represents, partly in vertical section and partly in elevation, a breech-loading drop-down hammer gun provided with automatic ejector mechanism constructed according to our said invention, and which said view represents the gun in its normal or fired position. Fig. 2 shows a similar view to Fig. 1, but with the barrels down and the spent-cartridge case ejected. Fig. 3 shows the gun cocked, while Fig. 4 represents an under side sectional view of the gun, showing the ejector-slides in duplicate and their operating-rods. Fig. 5 shows a part elevation and part section of the under sides of the barrels, thus exhibiting the rod which works the two halves of the divided extractor. Fig. 6 shows an end elevation of the breech ends of the barrels of the gun.

The same letters of reference indicate corresponding parts in Figs. 1 to 6, both inclusive, of the drawings.

a a are the barrels, and *b* is the body, of the gun.

b² is the face of the break-off, and *a²* are the breech ends of the barrels, having working and fitting within the face thereof a split or divided extractor, *c*, whose rods *c²* work within the solid metal of the under sides of the barrels. The forward ends of these rods are exposed, and against these the upwardly-extended ends *d²* of ejector-slides *d* take their

bearings or abutments. These slides *d* have guide-stems *d³*, whose front ends work through holes or eyes made in depending brackets *e³*, carried upon the under side of the fore-end iron, *e²*, of the fore-end *e*, while the other or rear ends of the said ejector-slides have slots, wherethrough the stems of pins *e⁴*, secured within the fore-end iron, pass. The stems *d³* of the ejector-slides *d* are encircled by coiled springs *d⁴*, whose ends abut against shoulders on the slides and the brackets *e³*, respectively. The back ends of the ejector-slides have bents or notches *d⁵*, wherein the nose ends *f²* of swinging ejector-sears *f* engage. The back ends of these sears are also provided with overhanging projections or outstanding parts *f³*, and when in the position as in Fig. 1 they come above the front ends of the liberating-rods *g*, which pass and work obliquely through the body of the arm.

The swinging sears *f* are hung upon pins or centers *f⁴*, and are kept up to their bents by a flat spring, *f⁵*, whose outer forked ends, respectively, press upon the rear top sides of the said sears, so as to make them snap into their bents on the slides being moved forward by the ejector-rods on the opening of the arm.

The divided extractor and the rods connected to the respective halves are collectively pressed rearwardly by a supplementary rod, *h*, working within the under side of the barrels, and with its back end coming against both halves of the extractor, as aforesaid. The rod is worked by the usual arm or snug, *i*, (see Fig. 5,) on the joint of the body part, so that on the breaking of the barrels the extractor-halves are pressed rearwardly through the intervention of the rod *h*.

The sear-releasing rods *g* are provided at their back ends with slides *j*, whose rear ends are prolonged upwardly into arms *j²*, against which the arms *k²* of rebound-tumblers *k* on the hammer-axes *l* of hammers *l* come on the gun being discharged by the falling of the said hammers. The tumblers *k* have full and half cock bents *k³ k⁴*, and are swivelly connected to the upper limbs, *m²*, of mainsprings *m* by swivel-connections *n*, and with the stand-side free ends *m³* of the said springs, taking

upon shoulders k^5 at the back of the tumblers, so as to make the lock a rebounding one.

o are sears proper, and o^2 are sear-springs.

5 The sear-releasing rods g have double-necked parts g^2 , wherein the free ends of springs g^3 respectively take on the rods being pushed forwardly or rearwardly, as herein-after described.

10 p is the tang-strap of the arm, q is the bolt-releasing lever, and r is the nipple, which is shown with the upper portion of the hammer in elevation.

15 The ejector mechanism is operated as follows, and as the two sides are alike I will only describe one of them.

20 On one of the barrels of the gun having been fired, the tumbler k , which is upon the hammer-axis, causes the arm k^2 to be urged or turned forward, so as to strike the arm j^2 of the slide j , and so force the said slide against the sear-releasing rod g , which is in its turn pressed forward into the position as 25 represented in Fig. 1, and held there by the free end of the spring g^3 passing into the back annular depression of the double-necked part g^2 . This forward movement of the rod brings its nose end g^4 under the overhanging projection f^3 of the ejector-sear f , so that on 30 the breaking of the barrels, as herein-after described, the sear is automatically released.

It must be observed that prior to the discharge of the arm the ejector-slide d has 35 been placed in that position, and the spring d^3 compressed by the forward movement of the extractor-rod c^2 of the extractor c on the closing of the arm, and such slide is held in 40 position, as in Fig. 1, ready for ejection by the ejector-sear nose f^2 engaging with the bent d^5 .

To open the barrels, turn the lever q aside, when the bolts are withdrawn and the barrels fall, as in Fig. 2. The falling of the barrels, when the parts are in the positions as 45 represented in Fig. 1, causes the nose end g^4 of the rod g , which was under the overhanging projection f^3 , to come against the under side of the said projection, and the breaking of the barrels and the dropping of the fore-end 50 with the barrels causes the ejector-sear f to be turned rearwardly upon its hanging fulcrum f^4 , which motion takes its nose end f^2 suddenly from out of the bent d^5 of the ejector-slide d , and so liberates the ejector-slide, which 55 strikes the front end of the ejector-rod c^2 with considerable impetus, thereby shooting outwardly and rearwardly the extractor, which flings or expels the cartridge-case s from the chamber of the barrel, leaving the other and 60 undischarged cartridge within its chamber, from which it has only been removed to the extracting distance, as effected by the arm or snug i pressing rearwardly the rod h —that is, the breaking of the barrels effects the slight 65 extraction of both cases by the rod h being pressed rearwardly by the slight angular movement made by the arm i . Thus the sud-

den release of the ejector-slide by the lifting of the rear side of the ejector-sear by the nose of the rod protruding through the joint part 70 allows the spring, which was under tension, to expend its released energy upon the slide, thus forcing it rearward with considerable impetus, striking the extractor-rod, which in its turn is suddenly and forcibly kicked backward, and the empty case with the barrel discharged expelled therefrom.

75 The breaking of the barrels causes the sear-releasing rod g to be pressed backward by the angle formed between the under side of the overhanging projection f^3 and the lower back part lying thereunder. In this position the rod is held by the free end of the spring g^3 passing into the front annular groove of the double-necked part g^2 .

80 The closing of the arm from the position Fig. 2 to that of Fig. 3 (without the haminer being cocked) causes the extractor end c to come against the face of the break-off b^2 , and as the barrels make their angular movement 85 inward the said extractors or extractor-segments are forcibly pressed inward or forward, and with the rods c^2 impressing themselves against the ends d^2 of both of the slides d , thereby pressing back the slide, compressing 90 the spring, and securing the slide in its forward position, as in Fig. 1, by the nose f^2 of the sear f engaging within the bent, as aforesaid.

95 The gun is cocked by hand by pressing back 100 the hammer l , so as to make the sear-nose take the full-cock bent and the arm k^2 of the tumbler k into a vertical position, as represented in Fig. 3, so that on the arm being discharged by the pulling of the trigger the cock 105 falls, which causes the tumbler-arm k^2 to strike the slide-arm j^2 and force forward the sear-releasing rod g into the position as represented at Fig. 1, with the nose end g^4 of the 110 said rod coming under the overhanging projection, which is lifted upward by the said nose end on the breaking of the barrels, as in Fig. 2.

Having thus described this invention, we claim as new and desire to secure by Letters Patent—

115 1. In a drop-down breech-loading hammer gun, the combination, with a body, b , rebounding lock-tumbler k k^2 k^3 k^4 k^5 , and hammer l , of an ejector-sear-releasing rod, g , and slide j , the rear of which latter is upwardly directed 120 into an arm, and against which the extended top part, k^2 , of tumbler k presses, and thereby moves the rod forward to engage the ejector-sear on the discharge of the arm, substantially as described and set forth.

125 2. The combination, in a hammer gun, of an ejector, ejector-sear, and ejector-sear-releasing rod g , slide j j^2 , and rebound-tumbler k , the slide being located between the tumbler k and rod g , substantially as shown and described.

130 3. The combination, with an ejector, ejector-sear, and ejector-sear-liberating rod g , having annular grooves g^2 , for engaging the springs

g^3 , of mechanism for projecting said rod longitudinally, as and for the purpose described and set forth.

4. The combination, with the barrels and body of a breech-loading gun, the ejector, and the ejector mechanism comprising the slide j^2 , rod g , and the hammer l , of the rebounding tumbler k , coupled to said hammer and provided with the upwardly-directed arm k^2 , adapted to impinge against said slide when the gun is discharged, substantially as set forth.

5. The combination, with ejector mechanism, substantially as described, and with the sear-operating rod g , of the ejector-sear f , pivoted in the frame at f^4 , with nose end f^2 and overhanging rear projection, f^3 , substantially as set forth.

6. The combination, with the barrels, body, and breech, of the ejector-sear-releasing rod g , the slide d^3 , attached to the stock, the hanging ejector-sear $f f^2 f^3 f^4$, arranged between the said rod and slide, and the extractor-rod c^2 , located behind and engaged by the slide d^3 , substantially as described.

7. The combination, with the fore-end and iron $e e^2$ and split extractor $c c^2$, of a slide, d ,

having upright hind part, d^2 , rising through a slot in said iron and impinging against said extractor, rod d^3 , spring d^4 , and bent d^5 , with ejector-sear $f f^2 f^3 f^4$, hung between said slide d and the nose of the releasing-rod g , and spring f^5 , substantially as described and set forth.

8. The combination, with the body, fore-end, and breech ends of the barrels of a hammer gun, of ejector mechanism consisting of a split extractor, c , located above the body of the gun, slide d , arranged in the fore-end, extractor-sear f behind said slide, ejector-sear-liberating rod g , fitted in the body of the gun, slide j , and rebound-tumbler k , located at the rear end of said rod, substantially as shown and described.

In testimony that we claim the foregoing we have hereunto set our hands this 13th day of December, 1887.
